AUTOMATIC TRAIN CONTROL

Paul J. Simmen, Eden, N. Y., assignor, by mesne assignments, to The Union Switch & Signal Company, Swissvale, Pa., a corporation of Pennsylvania

Refiled for abandoned application Serial No. 650,246, July 9, 1923. This application August 3, 1928, Serial No. 297,150

9 Claims. (Cl. 246—4)

This application is filed in lieu of abandoned application, Serial No. 650,246, filed July 9, 1923.

This invention relates to railway signalling, particularly to systems in which there is both automatic and manual control and more especially to those in which there are means for automatically indicating or recording the progress of trains.

This invention is an improvement on my invention disclosed in Reissue Letters Patent No. 17,384, dated July 30, 1929, and also an improvement on my invention disclosed in application for patent which was filed by me October 26, 1927, Serial No. 228,937. In Reissue No. 17,384 means are shown whereby an operator can change the signals on a section of track from one direction of train movement to the opposite direction, if there is no train in the section, the section being divided into a number of blocks so as to facilitate following train movements.

In Serial No. 228,937 filed October 26, 1927, means are shown to control two signals, clear and danger, for each direction of train movement. In the present invention four signals for the safe and quick direction of train movements for any number of sections of track are provided, each section being subdivided into several blocks, and controlled from a central point such as a dispatcher's office, interlocking tower, or way station by an operator, if there is no train in the section. That is, an operator having a plurality of sections of track under his control may set up four different signal indications for a train going in one direction but if there is no train in the section, he may instantly change so as to provide four signals for the direction of train movements in the opposite direction.

In order that the operator may intelligently govern train movements with the least delay, means are provided to automatically indicate or record the movement of trains at his office so that he has knowledge of the location and progress of all trains under his jurisdiction.

A further object of the invention is to prevent the operator from setting up proceed signals over a section of track for both an east bound and a west bound movement at the same time and to prevent him changing from one direction to the opposite as long as there is a train in the section.

Other objects and advantages will appear as the description of the particular physical embodiment of the invention and desirable modifications thereof selected to illustrate the invention progresses, and the novel features will be particularly pointed out in the appended claims.

In describing the invention in detail, reference is had to the accompanying drawings wherein I have illustrated a preferred physical embodiment of my invention and wherein like characters of reference designate corresponding parts throughout the several views and in which:

Fig. 1 is a schematic representation of the apparatus and circuits in the dispatcher's office and along the track; Fig. 2 is a schematic representation of the apparatus and circuits on the locomotive or car; and Fig. 3 is a modification of Fig. 1, and shows a schematic representation of part of the apparatus in the dispatcher's office and along the track by which fixed signals are displayed instead of cab signals.

Fig. 1 shows a single track consisting of rails 1 and 2. Rail 1 is electrically continuous. Rail 2 is divided into sections by means of insulating joints as 3 thus dividing the track into block sections as A, B, C, D, E, F, and G. In blocks B and F are shown sidings as 4 where trains can meet and pass each other. Since the apparatus and circuits for each single track section between passing sidings are identical, only one complete single track section has been shown in Fig. 1, but the dispatcher's control and the recording of train movements has been shown for two single track sections, thus switches as 5 and 6 control the signals of a section between blocks B and F and switches as 7 and 8 control the signals of a section east of block F. At the clearance point of the sidings insulating joints as 3 electrically separate the straight portion of the siding from the main track in a manner and for a purpose well known to those skilled in the art.

Each block is provided with a track circuit, a track battery as 16 being located at one end of each block and track relays as a, b, c, d, e, f, and g near the other ends of each block, constituting with their connections to the rails, a track circuit well known to those skilled in the art. Track relays b, d, and f control two armatures as 9 and 10 and track relays a, c, e, and g control three armatures as 9, 10, and 11. When there is no train in the block, the track relay for that block is energized and its armatures through their respective front contacts control certain signals, and when there is a train in the block, its track relay is deenergized and its armatures will close certain back contacts for the purpose of locking switches 5, 6, 7 and 8 and making a record of train movements as will be described in more detail hereinafter.

Adjacent to the track are located groups of 55

train control rails as A12 and A13, B12 and B13, C12 and C13, D12 and D13, E12 and E13, F12 and F13 and G12 and G13. The letter prefix as B to train control rails 12 and 13 indicate that 5 the rails are in block B and similarly for the others. Train control rails 12 and 13 are on the right hand side of the center line of the track looking east, and control each bound movements into a block, and a similar group of train 10 control rails on the opposite side of the track, that is, on the right hand side of the center line of the track looking west, control west bound train movements into a block. These west bound train control rails have been designated as A14 15 and A15, B14 and B15, C14 and C15, D14 and D15, E14 and E15, F14 and F15 and G14 and G15. In each group of train control rails, one is the home train control rail and located near the entrance to a new block and 20 the other is a distant train control rail and located approximately the braking distance from the home control rail. Thus train control rail 13 is the home train control rail for an east bound train movement and train control rail 14 is the home train control rail for a west bound train movement and train control rail 12 is the distant train control rail for an east bound train movement, and train control rail 15 is the distant train control rail for a west bound train 25 movement.

Manually operable switches 5 and 7 in the dispatcher's office when in position as shown in Fig. 1, make contact with spring contacts 17 and are thus connected to an alternating current 30 source as 20 and when these switches are disconnected from contact 17, the circuit from the alternating current source is broken. When switches 6 or 8 are in the right oblique position, they make electrical contact with spring contacts 40 as 18 and are thus connected with the positive pole of battery 21, and when switches 6 or 8 are in the left oblique position, making electrical contact with spring contacts as 19, they are connected with the negative pole of battery 22. 45 When switches 6 or 8 are open, they are disconnected from both direct current sources 21 and 22. Alternating current source 20 and direct current sources 21 and 22 are preferably located in the dispatcher's office.

50 The east bound train control rails for the section of track from B to F are connected through the several armatures of the track relay of the block ahead to a line wire as 23 and the west bound train control rails for the section of 55 track from F to B are connected through the several armatures of the track relay of the block ahead to a line wire as 24. Properly housed along the track are polarized relays as 25, shown in blocks B and F, one being necessary for 60 each section of single track between passing sidings. When polarized relay 25 is positively energized, its polarized armature as 26 will swing to the right as shown in Fig. 1, and an electrical connection is made between it and line wire 23, 65 through the contact 27 and when polarized relay 25 is negatively energized, its polarized armature will swing to the left, opposite to that shown in Fig. 1, and will make an electrical connection with line wire 24 through the contact 28.

70 When switches 6 or 8 are in the right oblique position making contact with spring contact 18, polarized relay 25 is positively energized, and when in the left oblique position, thus making contact with spring contact 19, relay 25 is negatively energized, and when switches 6 or 8 are

disconnected from either spring contact 18 or 19, polarized relay 25 is deenergized and neutral armature 29 will break away from front contact 30.

Polarized relay 25 which controls the section 5 between blocks B and F is positively energized through the following circuit: From positive pole of battery 21, wire 31, impedance 32, bus 33, wire 34, spring contact 18, switch 6, shaft 35, wire 36, relay 37, wire 38, impedance 39, wire 50, 10 terminal 51, wire 52, terminal 53, wire 40, polarized relay 25, wire 41, resistance 42, wire 43, impedance 44, wire 45, track rail 1, and wires 46 and 47, to negative pole of battery 21.

Relay 25 is negatively energized through the 15 following circuit: From positive pole of battery 2, wires 48, 49 and 46, track rail 1, wire 45, impedance 44, wire 43, resistance 42, wire 41, polarized relay 25, wire 40, terminal 53, wire 52, terminal 51, wire 50, impedance 39, wire 38, relay 20 37, wire 36, shaft 35, switch 6, spring contact 19, wire 54, bus 55, impedance 56, wire 57, to negative pole of battery 22.

Impedances 32, 39, 44 and 56 are inserted in the circuit to prevent the flow of alternating 25 current in the circuit and resistance 42 is inserted in the circuit for a purpose which will be more fully described hereinafter.

When the dispatcher places switch 6 in contact with spring contact 18, polarized relay 25 is 30 positively energized and thus all east bound train control rails between blocks B and F are electrically connected to battery 21 in the dispatcher's office by reason of polarized armature 26 making contact with contact 27. Under these conditions 35 however all west bound train control rails between blocks F and B are deenergized, since polarized armature 26 is disconnected from contact 28. When the dispatcher places switch 6 in contact with spring contact 19, polarized relay 40 25 is negatively energized and thus all west bound train control rails between blocks F and B are electrically connected to battery 22 in the dispatcher's office by reason of polarized armature 26 making contact with contact 28. Under these 45 conditions however all east bound train control rails between blocks B and F are deenergized since polarized armature 26 is disconnected from contact 27. When the east bound train control 50 rails are connected through polarized armature 26 and contact 27 to switch 6, they may be also charged with alternating current from alternating current source 20 through a circuit which will be more fully described hereinafter and similarly when the west bound train control rails 55 are connected through polarized armature 26 and contact 28, they may also be charged with alternating current.

Since the circuits to the east bound train control rails for the positive direct current and the 60 alternating current are common from polarized armature 26 to the train control rails, I will first describe the positive direct current from battery 21 to polarized armature 26, which is as follows: From positive pole of battery 21, wire 31, impedance 32, bus 33, wire 34, spring contact 18, switch 6, shaft 35, wire 36, relay 37, wire 38, impedance 39, wire 50, terminal 51, wire 52, terminal 53, wire 58, armature 29 of relay 25, front contact 30, wire 59, polarized armature 26, to contact 27. 70 The alternating current circuit is as follows: From alternating current source 20, wire 60, condenser 61, bus 62, wire 63, spring contact 17, switch 5, shaft 35, wire 64, alternating current relay 65, wire 66, condenser 67, wire 68, terminal 75

51, wire 52, terminal 53, wire 58, armature 29, front contact 30, wire 59, polarized armature 26, contact 21. In the event that polarized relay 25 being deenergized by reason of switch 6 being open, a by-pass circuit is provided for the alternating current as follows: From terminal 53, wire 69, condenser 70, and wire 71, to polarized armature 26, the purpose of which will be more fully explained hereinafter. Condensers 61, 67, and 70 are inserted in the circuits to prevent the flow of direct current in the circuit.

The circuit from polarized armature 26 for both positive direct current and alternating current to train control rails B12 and B13 is as follows: From polarized armature 26, contact 27, line wire 23, wire 72, armature 9 of track relay c, front contact 73, wire 76, to train control rails B13 and B12, and thence the circuit is completed to the current source in the dispatcher's office as will be more fully described hereinafter. The circuit from polarized armature 26 to train control rails C12 and C13 is as follows: From polarized armature 26, contact 27, line wire 23, wire 77, armature 9 of track relay d, front contact 73, wire 78 to train control rails C13 and C12. The circuit to train control rails D13 and D12 is as follows: From polarized armature 26, contact 27, line wire 23, wire 79, armature 9 of track relay e, contact 73, wire 80, to train control rails D13 and D12. The circuit to train control rails E12 and E13 is as follows: From polarized armature 28, contact 27, line wire 23, wire 81, armature 9 of track relay f, front contact 73, wire 82, armature 11 of track relay g, front contact 75, wire 83, to train control rails E13 and E12. Through these two circuits, the positive direct current circuit and the alternating current circuit, east bound train control rails may be electrically conditioned in four different ways as follows:

40 *First condition.*—When switch 6 is in contact with spring contact 18 and switch 5 is in contact with spring contact 17, the east bound train control rails are charged with positive direct current and alternating current.

45 *Second condition.*—When switch 6 is in contact with spring contact 18 and switch 5 is disconnected from spring contact 17, the east bound train control rails are charged with positive direct current only.

50 *Third condition.*—When switch 6 is disconnected from spring contact 18 and switch 5 is in contact with spring contact 17, the east bound train control rails are charged with alternating current only.

55 *Fourth condition.*—When switch 6 is disconnected from spring contact 18 and switch 5 disconnected from spring contact 17, the east bound train control rails are deenergized.

By reason of these four different electrical conditions, four different signals may be displayed on the east bound locomotive when the locomotive is passing a train control rail, as will be more fully described hereinafter.

When the dispatcher places switch 6 in contact with spring contact 19, polarized relay 25 is negatively energized and all west bound train control rails are electrically connected through polarized armature 26 and contact 28 and under these conditions west bound train control rails may also be charged with alternating current as hereinbefore stated.

Since the circuit to the west bound train control rails for the negative direct current, and the alternating current, are common from polarized armature 26, to the train control rails, I will first

describe the negative direct current circuit from battery 22 to polarized armature 26 which is as follows: From negative pole of battery 22, wire 57, impedance 56, bus 55, wire 54, spring contact 19, switch 6, shaft 35, wire 36, relay 37, wire 38, impedance 39, wire 50, terminal 51, wire 52, terminal 53, wire 58, armature 29, of polarized relay 25, front contact 30, wire 59, polarized armature 26, to contact 28.

The alternating current circuit for charging west bound train control rails with alternating current as far as polarized armature 26 is concerned is the same as hereinbefore described.

The circuit from polarized armature 26 for both negative direct current and alternating current to train control rails F14 and F15 is as follows: From polarized armature 26, contact 28, line wire 24, wire 84, armature 10 of track relay e, front contact 74, wire 85, to train control rails F14 and F15 and thence the circuit is completed to the current sources in the dispatcher's office as will be more fully described hereinafter. The circuit to train control rails E14 and E15 is as follows: From polarized armature 26, contact 28, line wire 24, wire 86, armature 10 of track relay d, front contact 74, and wire 87 to train control rails E14 and E15. The circuit to train control rails D14 and D15 is as follows: From polarized armature 26, contact 28, line wire 24, wire 88, armature 10 of track relay c, front contact 74, and wire 89, to train control rails D14 and D15. The circuit to train control rails C14 and C15 is as follows: From polarized armature 26, contact 28, line wire 24, wire 90, armature 11 of track relay a, front contact 75, wire 91, armature 10 of track relay b, front contact 74, and wire 92, to train control rails C14 and C15. Through these two circuits, the negative direct current circuit and the alternating current circuit, west bound train control rails may be electrically conditioned in four different ways as follows:

40 *First condition.*—When switch 6 is in contact with spring contact 19 and switch 5 is in contact with spring contact 17, the west bound train control rails are charged with negative direct and alternating current.

45 *Second condition.*—When switch 6 is in contact with spring contact 19 and switch 5 is disconnected from spring contact 17, the west bound train control rails are charged with negative direct current only.

50 *Third condition.*—When switch 6 is disconnected from spring contact 19, and switch 5 is in contact with spring contact 17, the west bound train controls rails are charged with alternating current only.

55 *Fourth condition.*—When switch 6 is disconnected from spring contact 19, and switch 5 is disconnected from spring contact 17, the west bound train control rails are deenergized.

60 By reason of these four different electrical conditions, four different signals may be displayed on a west bound locomotive, when a locomotive is passing a train control rail, as will be more fully described hereinafter.

65 It will thus be seen that the dispatcher may condition the single track section between blocks B and F for an east bound train movement by placing switch 6 in contact with spring contact 18 under which conditions all east bound train control rails in the section may be electrically conditioned in four different ways as hereinbefore described and when the dispatcher places switch 6 in contact with spring contact 19, the single track section from block F to block B is conditioned

for a west bound train movement and similarly the train control rails may be electrically conditioned in four different ways as hereinbefore described. In addition to the dispatcher's manual control of the electrical conditions of the train control rails, automatic control is also provided by means of a track circuit. Assume that there is no train in any of the blocks between B and E, and the dispatcher has set up an east bound movement by placing switch 6 in contact with spring contact 18 and a train received a clear signal at train control rail B13 and proceeds into block C, then as soon as the train entered block C, the current from track battery 16 of block C 15 is short circuited through the wheels and axles of the train and therefore track relay c becomes sufficiently deenergized so that its armatures will drop away from the front contacts. When this occurs train control rails B12 and B13 become 20 deenergized since the circuit is now broken by armature 9 of track relay c dropping away from front contact 73. As soon however as the train has left block C and entered block D, track relay c again becomes energized thus again closing the 25 circuit to train control rails B12 and B13 and a second train may proceed eastward with a clear signal. It will therefore be seen that a train which proceeds over the road automatically protects itself in the rear, so that a following train 30 will automatically receive a danger signal when it arrives within braking distance of a train ahead. The same automatic rear end protection by means of a track circuit is also provided for west bound movements. For instance a west 35 bound train entering block E will deenergize track relay e, thus breaking the circuit at front contact 74 of track relay e and deenergizing west bound train control rails F14 and F15. As soon, however, as the train has left block E, train control 40 rails F14 and F15 are again energized thus permitting a following train to proceed with a clear signal.

It will be noted that the circuit to train control rails E12 and E13 and G14 and G15 are taken 45 through the armatures of both track relays f and g and f and e, the object being as follows: If the dispatcher has placed switch 6 in contact with spring contact 18, thus setting up an east bound movement for a train from block B to block F and 50 also placed switch 8 in contact with spring contact 19, thus setting up a west bound movement for a train from block G to block F, the two trains will have to meet and pass each other at the siding in block F. If now the east bound train entered 55 block E approximately at the same time that the west bound train entered block G, each train will automatically receive a danger signal, by reason of the track circuit control, before reaching block F and this will give the trains ample 60 distance to slow down or stop until one of the trains has taken the siding. This arrangement is desirable if block F and the siding are relatively short. While this arrangement shows the preferred form, it is not absolutely necessary particularly if block F and the siding are relatively 65 long. The arrangement of taking the circuit to the train control rails through two track relays, can also be obviated by placing the distant train control rails F12 and F15, a sufficient distance 70 back to give the engineer ample warning to stop for the meet. Switches 7 and 8 control the single track section east of block F through polarized relay 25 at block F in the identical manner as described for the section of B to F, and where 75 the dispatcher controls the train movements over

a large number of single track sections from one central point, duplicate control switches as 5 and 6 with their corresponding circuits are provided for each section.

The system is so arranged that when the dispatcher has set up an east bound movement from block B to block F by placing switch 6 in contact with spring contact 18, as soon as the train enters block C after receiving a clear signal at B13, switch 6 is automatically locked in the position it is in, so that it cannot be moved by the dispatcher, and the switch remains locked until after the train has passed out of block E. This is accomplished in the following manner: Switches 6 and 8 are rotatable on a shaft as 35. Secured to the shaft is a disk as 93. In the periphery of this disk are two notches as 94 and 95. The armature 96 of relay 37 is hinged at 97. At the other end of armature 96, is a detent as 98 so positioned that when switch 6 is in contact with spring contact 18, detent 98 will be in alignment with notch 94 and when switch 6 is in contact with spring contact 19, detent 98 is in alignment with notch 95. When relay 37 is sufficiently energized it will attract its armature 96 and if 25 detent 98 is in alignment with either notch 94 or 95, it will engage one of the notches, thus preventing the switch from being turned from the position it is in as long as relay 37 is sufficiently energized. When relay 37 is not sufficiently energized, a spring as 99 pulls detent 98 out of engagement with the notches in disk 93. When switch 6 is in contact with spring contact 18, the normal position for an east bound train movement, and there is a train in either blocks 35 C, D, or E, relay 37 is sufficiently energized and thus the switch is locked as long as the train remains in the blocks C, D, or E. When block C is occupied by an east bound train, relay 37 is energized through the following circuit: From 40 positive pole of battery 21, wire 31, impedance 32, bus 33, wire 34, spring contact 18, switch 6, shaft 35, wire 36, relay 37, wire 38, impedance 39, wire 50, terminal 51, wire 52, terminal 53, wire 58, armature 29 of polarized relay 25, front contact 30, wire 59, polarized armature 26, contact 27, line wire 23, wire 72, armature 9 of track relay c, back contact 100, wire 102, track rail 1, and wires 46 and 47 to negative pole of battery 21. When this circuit is closed relay 37 is sufficiently 50 energized to attract armature 96 against the tension of spring 99 so as to lock switch 6, for the reason that a shunt circuit is now established which cuts out the resistance 42 in the circuit controlling polarized relay 25. When block D is 55 occupied relay 37 is energized thus locking switch 6 through the following circuit: From positive pole of battery 21, wire 31, impedance 32, bus 33, wire 34, spring contact 18, switch 6, shaft 35, wire 36, relay 37, wire 38, impedance 39, wire 50, terminal 51, wire 52, terminal 53, wire 58, armature 29, front contact 30, wire 59, polarized armature 26, contact 27, line wire 23, wire 77, armature 9 of track relay d, back contact 100, wire 103, track rail 1, and wires 46 and 47 to negative pole 60 of battery 21. When block E is occupied, relay 37 is energized, thus locking switch 6 through the following circuit: From positive pole of battery 21, wire 31, impedance 32, bus 33, wire 34, spring contact 18, switch 6, shaft 35, wire 36, relay 37, wire 38, impedance 39, wire 50, terminal 51, wire 52, terminal 53, wire 58, armature 29, front contact 30, wire 59, polarized armature 26, contact 27, line wire 23, wire 79, armature 9 of track relay e, back contact 100, wire 104, track rail 1, 70 75

and wires 46 and 47 to negative pole of battery 21. It will thus be seen that as long as an east bound train occupies either blocks C, D, or E detent 98 engages notch 94 thus locking switch 6 in the position it is in.

When switch 6 is in contact with spring contact 19, the normal position for a west bound train movement, and there is a train in either blocks E, D, or C, relay 37 is sufficiently energized and thus the switch is locked, as long as the train remains in blocks E, D, or C. When block E is occupied, relay 37 is energized thus locking switch 6 through the following circuit: From positive pole of battery 22, wires 48, 49 and 46, track rail 1, wire 104, back contact 101, armature 10 of track relay e, wire 84, line wire 24, contact 28, polarized armature 26 of relay 25, wire 59, front contact 30, armature 29, wire 58, terminal 53, wire 52, terminal 51, wire 50, impedance 39, wire 38, relay 37, wire 36, shaft 35, switch 6, spring contact 19, wire 54, bus 55, impedance 56, and wire 57 to negative pole of battery 22. When block D is occupied, relay 37 is energized thus locking switch 6 through the following circuit: From positive pole of battery 22, wires 48, 49 and 46, track rail 1, wire 103, back contact 101, armature 10 of track relay d, wire 86, line wire 24, contact 28, polarized armature 26, wire 59, front contact 30, armature 29, wire 58, terminal 53, wire 52, terminal 51, wire 50, impedance 39, wire 38, relay 37, wire 36, shaft 35, switch 6, spring contact 19, wire 54, bus 55, impedance 56, and wire 57 to negative pole of battery 22. When block C is occupied, relay 37 is energized thus locking switch 6 through the following circuit: From positive pole of battery 22, wires 48, 49 and 46, track rail 1, wire 102, back contact 101, armature 10 of track relay c, wire 88, line wire 24, contact 28, polarized armature 26, wire 59, front contact 30, armature 29, wire 58, terminal 53, wire 52, terminal 51, wire 50, impedance 39, wire 38, relay 37, wire 36, shaft 35, switch 6, spring contact 19, wires 54 and 55, impedance 56, and wire 57 to negative pole of battery 22.

It will thus be seen that when the dispatcher has set up an east bound movement from block B to block E and a train has accepted a clear or proceed signal and has entered block C, the dispatcher is unable to change the position of switch 6 until the train has left block E and when the dispatcher has set up a west bound movement from block F to block C and a train has accepted a clear or proceed signal and has entered block E, the dispatcher is unable to change the position of switch 6 until the train has left block C. In other words the dispatcher is unable to give a proceed signal to both an east bound train and a west bound train at the same time between two points where trains may pass each other.

It will be noted that track relay b and f are not provided with back contacts. This back contact has been omitted in the preferred form so that switches 5, 6, 7, and 8 will be unlocked as soon as a train has left the single track portion of the railroad and has entered a siding block such as B or F. It is desirable in the preferred form to give the dispatcher full liberty in placing switches in the positions desired as soon as the train has reached the main track or the siding of block B or F. A similar locking means may also be provided for alternating current switches 5 and 7. The locking means are the same except that only one notch as 105 is necessary on disk 93. Relay 65, is one responding to

alternating current. When switch 5 is in contact with spring contact 17 and an east bound train has entered block C, relay 65 becomes sufficiently energized thus locking switch 5 in the position it is in through the following circuit: From alternating current sources 20, wire 60, condenser 61, wires 62 and 63, spring contact 17, switch 5, shaft 35, wire 64, relay 65, wire 66, condenser 67, wire 68, terminal 51, wire 52, terminal 53, wire 58, armature 29, front contact 30, wire 59, polarized armature 26, contact 27, line wire 23, wire 72, armature 9 of track relay c, back contact 100, wire 102, track rail 1, and wires 46, 49 and 106 to alternating current source 20.

Since the circuits for the purpose of locking switch 5 through blocks D and E for both east bound as well as west bound movements are similar, as the circuits described for switch 6, it is thought not necessary to describe these in further detail.

Under some conditions of operation under this system, it may be desirable not to lock switches 5 and 7, controlling the alternating current in the position they are in, even if blocks E, D and C are occupied, so as to give the dispatcher the liberty to move this switch to the closed or open position at all times, in which case the locking feature for these switches 5 and 7 may be omitted.

I will now describe the apparatus on the locomotive or car capable of displaying four different signals corresponding to the four different electrical conditions of the train control rail when passing a train control rail, and also how these signals are continued after the locomotive has passed the train control rail. In Fig. 2, are shown four signals designated as No. 1, No. 2, No. 3, and No. 4. While these devices are shown as lamps and designated signals, they may equally as well represent an electro-magnetic device to which motion is given, depending upon whether the circuit is energized or deenergized and such electro-magnetic devices may be used for other purposes than, or in addition to, the display of signals to the engineer, such as is well known in the art, the proper control of speed control devices or pneumatic air valves or both.

Signal No. 1 is displayed when the locomotive is passing a train control rail which is positively energized with direct current and alternating current. Signal No. 2, when the locomotive is passing a train control rail which is energized with positive or negative direct current only. Signal No. 3 is displayed when the locomotive is passing a train control rail which is energized with alternating current only. Signal No. 4 is displayed when the locomotive is passing a train control rail which is entirely deenergized.

In Fig. 2 is shown an electrical contact shoe as 107 so positioned on the locomotive as to make contact with train control rails. The contact shoe is hinged at 108. The train control rails are inclined at the ends so as to form a ramp in the usual manner such as is shown in my prior Patent No. 1,140,623 granted May 25, 1915. When the contact shoe slides along this ramp the shoe is tilted so as to break contacts as 109, 110 and 111. When the shoe leaves the other end of the train control rail, a spring as 112 forces the contact shoe to the normal position, thus again closing contacts 109, 110 and 111.

The locomotive also carries a polarized relay as 113, an alternating current relay as 114 with its direct current coil as 115, and two batteries as 116 and 117. Polarized relay 113 controls three neutral armatures as 118, 119 and 120 and two

polarized armatures as 121 and 122. Polarized armatures 121 and 122 are members of a pole changing switch for the purpose of changing the direction of the flow of current from battery 116. 5 When polarized relay 113 is positively energized its neutral armatures make contact with front contacts as 123, 124 and 125 and its polarized armatures are in the position shown in Fig. 1, and make contact with contacts 126 and 127. 10 When polarized relay 113 is negatively energized, its neutral armatures make contact with their respective front contacts but the polarized armatures are now in the position opposite to that shown in Fig. 2, and make contact with 15 contacts 128 and 129. When polarized relay 113 is deenergized, its neutral armatures 119 and 120 make contact with back contacts 130 and 131. When alternating current relay 114 or its companion direct current coil 115 is energized, its 20 armatures 132 and 133 make contact with front contacts 134 and 135 and when this relay is deenergized, armature 133 makes contact with back contact 136.

When an east bound locomotive is passing an 25 east bound train control rail as for instance B13, which is energized with positive direct current and alternating current, polarized relay 113 is positively energized through the following circuit: From positive pole of battery 21, wire 31, impedance 32, bus 33, wire 34, spring contact 18, switch 6, shaft 35, wire 36, relay 37, wire 38, impedance 39, wire 50, terminal 51, wire 52, terminal 53, wire 58, armature 29, front contact 30, wire 59, polarized armature 26, contact 27, line 35 wire 23, wire 72, armature 9 of track relay e, front contact 73, wire 76, train control rail B13, contact shoe 107, wires 137 and 138, impedance 139, wire 140, polarized relay 113, wires 141, 142, 143 and 144, resistance 145, wire 146, axle 147, 40 wheel 148, track rail 1, and wires 46 and 47 to negative pole of battery 21. A circuit is also established through alternating current relay 114 as follows: From alternating current source 20, wire 60, condenser 61, bus 62, wire 63, spring 45 contact 17, switch 5, shaft 35, wire 64, relay 65, wire 66, condenser 67, wire 68, terminal 51, wire 52, terminal 53, wire 58, armature 29, front contact 30, wire 59, polarized armature 26, contact 27, line wire 23, wire 72, armature 9 of track 50 relay c, front contact 73, wire 76, train control rail B13, contact shoe 107, wires 137 and 149, condenser 150, wire 151, alternating current relay 114, wires 152, 142, 143 and 144, resistance 145, wire 146, axle 147, wheel 148, track rail 1, 55 and wires 46, 49 and 106 to alternating current source 20. With relay 113 positively energized and relay 114 energized, a circuit is established through signal No. 1, as follows: From positive pole of battery 116, wires 153 and 154, contact 60 126, polarized armature 121, wires 155 and 156, armature 133 of relay 114, front contact 135, wire 157, armature 119 of relay 113, front contact 124, wire 158, signal No. 1, wires 159, 160, 143 and 161, polarized armature 122, contact 65 127, and wire 162 to negative pole of battery 116. When the contact shoe 107 leaves the other end of the train control rail, the contacts 109, 110 and 111 are again closed and two stick circuits are established, a positive direct current stick 70 circuit and an alternating current stick circuit. The positive direct current stick circuit is as follows: From positive pole of battery 116, wires 153 and 154, contact 126, polarized armature 121, wires 155, and 163, armature 118, of relay 75 113, front contact 123, wire 164, contact 109,

contact shoe 107, wires 137 and 138, impedance 139, wire 140, polarized relay 113, wires 141, 142 and 161, polarized armature 122, contact 121, and wire 162 to negative pole of battery 116. The alternating current relay stick circuit is as follows: From battery 117, wire 165, coil 115 of relay 114, wire 166, contact 111, metallic contact plate 167, contact 110, wire 168, front contact 134, armature 132, of relay 114, and wire 169, to negative pole of battery 117. Metallic plate 167 is attached to contact shoe 107 but insulated therefrom, so that when the contact shoe slides on a train control rail, contacts 110 and 111 are broken. With the positive direct current stick circuit and the alternating current relay stick circuit in effect, signal No. 1 is continued until the next train control rail is reached. 15

Assuming now that an east bound train is passing train control rail B13 and this rail is energized with positive direct current only 20, then polarized relay 113 on the locomotive will be positively energized through the circuit hereinbefore described, but alternating current relay stick circuit was broken as soon as the contact shoe 107 slid onto the rail 25 B13 by reason of contact 109 being broken and there being no alternating current in the train control rail, relay 114 became deenergized. Under these conditions a circuit is established through signal No. 2 as follows: From positive 30 pole of battery 116, wires 153 and 154, contact 126 polarized armature 121, wire 155 and 156, armature 133 of relay 114, back contact 136, wire 170, armature 120, of relay 113, front contact 125, wire 171, signal No. 2, wires 172, 173, 160, 35 143 and 161, polarized armature 122, contact 127, and wire 162 to the negative pole of battery 116. When the contact shoe leaves the other end of the train control rail, the positive direct current stick circuit is again established as herein- 40 before described but the alternating current relay stick circuit is still inoperative. While contact 109 is again closed through contact shoe 107, this stick circuit is now open at front contact 134. Thus signal No. 2 will be continued 45 until the next train control rail is reached.

Assuming now that an east bound train is passing train control rail B13 and this rail is energized with alternating current only, then polarized relay 113 on the locomotive will be deenergized since the positive direct current stick circuit is now open at contact 109, but alternating current relay 114 will be energized through the circuit as hereinbefore described, with this difference however that since the circuit is now open at armature 29 and front contact 30 by reason of polarized relay 25 being energized, the alternating current will reach train control rail B13 through the by-pass from terminal 53 to polarized armature 26 as hereinbefore described. 55 With alternating current relay 114 energized but polarized relay 113 deenergized, a circuit is established through signal No. 3 as follows: From positive pole of battery 116, wires 153 and 154, contact 126, polarized armature 121, wires 155 and 156, armature 133 of relay 114, front contact 135, wire 157, armature 119 of relay 113, back contact 130, wire 174, signal No. 3, wires 175, 173, 160, 143 and 161, polarized armature 122, contact 127, and wire 162, to negative pole of battery 116. When the contact shoe leaves the other end of the train control rail, the alternating current relay stick circuit is again established as hereinbefore described but the positive direct current stick circuit is now inoperative 70 75

since this circuit is now open at front contact 123, thus signal No. 3, is continued until the next train control rail is reached.

Assuming now that an east bound train is passing train control rail B13 and this rail is deenergized, then both relays 113 and 114 on the locomotive become deenergized since the positive direct current stick circuit is now open at contact 109, and the alternating current stick circuit 10 is now open at contacts 110 and 111. Under these conditions a circuit is closed through signal No. 4, as follows: From positive pole of battery 116, wires 153 and 154, and contact 126, polarized armature 121, wires 155 and 156, armature 133 15 of relay 114, back contact 136, wire 170, armature 120 of relay 113, back contact 131, wire 176, signal No. 4, wires 177, 173, 160, 143, and 161, polarized armature 122, contact 127, and wire 162, to negative pole of battery 116. Assuming now that the 20 train proceeds with signal No. 4 showing, then contacts 109, 110 and 111, of the stick circuit are again closed as soon as the contact shoe has left the train control rail, but both stick circuits are inoperative since front contacts 123 and 134 are 25 now open.

A similar control of the four signals takes place on a west bound train. Assuming now that a west bound locomotive is passing train control rail F14 which is energized with negative direct 30 current and alternating current, then polarized relay 113 on the locomotive will be negatively energized through the following circuit: From positive pole of battery 22 in the dispatcher's office, wires 48, 49 and 46, track rail 1, wheel 35 48, axle 147, wire 146, resistance 145, wires 144, 143, 142 and 141, polarized relay 113, wire 140, impedance 139, wires 138 and 137, contact shoe 107, train control rail F14, wire 85, contact 74, armature 10 of track relay e, wire 84, line wire 40 24, contact 28, polarized armature 26, wire 59, front contact 30, armature 29, wire 58, terminal 53, wire 52, terminal 51, wire 50, impedance 39, wire 38, relay 37, wire 36, shaft 35, switch 6, spring contact 19, wire 54, bus 55, impedance 56, 45 wire 57, to negative pole of battery 22. A circuit is also established through alternating current relay 114 as follows: From alternating current source 20, wire 60, condenser 61, bus 62, wire 63, spring contact 17, switch 5, shaft 35, wire 64, 50 relay 65, wire 66, condenser 67, wire 68, terminal 51, wire 52, terminal 53, wire 58, armature 29, front contact 30, wire 59, polarized armature 26, contact 28, line wire 24, wire 84, armature 10 of track relay e, front contact 74, wire 85, train 55 control rail F14, shoe 107, wires 137 and 149, condenser 150, wire 151, relay 114, wires 152, 142, 143 and 144, resistance 145, wire 146, axle 147, wheel 148, track rail 1, and wires 46, 49 and 106, to alternating current source 20. With 60 polarized relay 113 negatively energized, its polarized armatures 121 and 122 assume the position opposite to that shown in Fig. 2, thus making contact with contacts 128 and 129 and with relay 114 also energized a circuit is established through 65 signal No. 1, as follows: From positive pole of battery 116, wires 153 and 178, contact 129, polarized armature 122, wires 161, 143, 160 and 159, signal No. 1, wire 158, front contact 124, armature 119, wire 157, front contact 135, armature 133, wires 156 and 155, polarized armature 121, contact 128, and wire 162 to negative pole of battery 116. When the contact shoe leaves the other end of the train control rail, a negative direct current stick circuit through relay 113 is 70 established as follows: From positive pole of 75

battery 116, wires 153 and 178, contact 129, polarized armature 122, wires 161, 142 and 141, polarized relay 113, wire 140, impedance 139, wires 138 and 137, contact shoe 107, contact 109, wire 164, front contact 123, armature 118, wires 5 163 and 155, polarized armature 121, contact 128, and wire 162 to negative pole of battery 116. The alternating current relay stick circuit is also established as hereinbefore described, thus signal No. 1, will be continued until the next train 10 control rail is reached.

Assuming now that a west bound train is passing train control rail F14 and this rail is energized with negative direct current only, then polarized relay 113 will be negatively energized through the 15 circuit hereinbefore described, but alternating current relay 114 will be deenergized. Under these conditions a circuit will be established through signal No. 2 as follows: From positive pole of battery 116, wires 153 and 178, contact 129, 20 polarized armature 122, wires 161, 143, 160, 173, and 172, signal No. 2, wire 171, front contact 125, armature 120, wire 170, back contact 136, armature 133, wires 156 and 155, polarized armature 121, contact 128, wire 162, to negative pole of 25 battery 116. When the contact shoe leaves the other end of the train control rail, the negative direct current circuit is again established but the alternating current relay stick circuit is now inoperative, thus signal No. 2 is continued. 30

Assuming now that a west bound train passes train control rail F14 and this rail is energized with alternating current only, then polarized relay 113 will be deenergized and alternating current relay 114 will be energized. Under these conditions a circuit will be established through signal No. 3, as follows: From positive pole of battery 116, wires 153 and 178, contact 129, polarized armature 122, wires 161, 143, 160, 173, and 175, signal No. 3, wire 174, back contact 130, armature 119, wire 157, front contact 135, armature 133, wire 156, and 155, polarized armature 121, contact 128, and wire 162 to negative pole of battery 116. 40

Assuming now that a west bound train is passing 45 a train control rail F14 and this train control rail is deenergized, then both relays 113 and 114 become deenergized since the negative direct current stick circuit and the alternating current relay stick circuit are both inoperative. Under these 50 conditions a circuit is closed through signal No. 4, as follows: From positive pole of battery 116, wires 153 and 178, contact 129, polarized armature 122, wires 161, 143, 160, 173 and 177, signal No. 4, wire 176, back contact 131, armature 120, wire 170, back contact 136, armature 133, wires 156 and 155, polarized armature 121, contact 128, and wire 162 to the negative pole of battery 116. Assuming now that the train proceeds with signal 55 No. 4 showing, then both the stick circuits will still be inoperative and thus signal No. 4 is continued. 60

Having described the circuits controlling the cab relays when an east bound train is passing train control rails B13 and a west bound train 65 is passing train control rail F14, it is thought not necessary to describe the circuits to other train control rails as these are identical with the exception of the particular branch circuit to a particular train control rail which have all been 70 hereinbefore described.

Resistance 139 is inserted in the cab circuit to prevent the flow of alternating current through the circuit and condenser 150 is inserted in the cab circuit to prevent the flow of direct current 75

through the circuit. Resistance 145 is inserted in the cab circuit for the following purpose: When there is a train in blocks C, D or E, current is flowing through relays 37 and 65 in the dispatcher's office thus locking switches 6 and 5 in the position they are in as hereinbefore described. When contact shoe 107 on the locomotive is passing an energized train control rail, current is also flowing through relays 37 and 65, but by reason of the combined resistance of relay 113 and resistance 145, or relay 114 and resistance 145, there is not sufficient current flowing through these relays to attract their armatures 96 against the tension of spring 99, therefore, a train passing a train control rail which is energized will not lock switches 5 or 6. For instance, it is desirable when there is a train in block B that the switches governing the adjacent sections of track be unlocked and it is possible that a contact shoe on a locomotive may be in contact with either train control rails B12 or B13 or B14 or B15 and this would lock the switches if the current flow through either relay 37 or 65 is not reduced as arranged by the introduction of the necessary resistance 145 in the cab circuit.

The four signals on the locomotive may be used for any purpose the railway management specifies. For instance, signals No. 1 and No. 4 may be used for safety purposes, signal No. 1 indicating to the engineer to proceed, that the track ahead is clear and signal No. 4 to stop, that there is danger ahead. Signal No. 2 may be used for facility purposes, thus signal No. 2 may indicate to an engineer to stop at the next siding, pull in on the siding and pass another train, while signal No. 3 may indicate to the engineer to stop at the next siding and report to the dispatcher.

I will now describe the means by which a record is made or an indication is given in the dispatcher's office of the movement of trains. In the dispatcher's office is a suitably mounted record sheet as 178 driven by a roller as 179 which in turn is driven by a shaft as 180. Shaft 180 receives motion through ratchet wheel as 181. A pawl as 182 is pivotally attached to armature 183 of electromagnet as 184, the armature being hinged at 185. When electromagnet 184 is periodically energized motion is given to ratchet wheel 181 by pawl 182. A spring as 186 normally pulls armature 183 and pawl 182 to the right when electromagnet 184 is not energized. Electromagnet 184 is connected by wire 187 to a make and break device as 188, which make and break device is periodically operated by a clock as 189. This may well be of the form as shown in my prior Patent No. 1,203,146 granted October 21, 1916. When the make and break device is closed, electromagnet 184 is energized through the following circuit: From battery 190, wires 191 and 192, electromagnet 184, wire 187, make and break device 188, wire 193, and wire 194, to the other side of battery 190. The make and break device 188 is operated say every five seconds, so as to give a slow and uniform motion to record sheet 178 through ratchet wheel 181 and pawl 182.

The record sheet 178 is transversely divided into sections as 195 and 196, each section representing a section of single track between passing sidings or other points where trains may pass each other. The record sheet is longitudinally divided into time lines, such as 1 A. M., each one of the lines representing a one minute interval. It will thus be seen that longitudinally the record sheet assumes a constantly changing position 75 during the 24 hours of the day.

Adjacent to the record sheet are located perforating magnets as 197, 198 and 199, three for each section of single track. These perforating magnets control armatures 200. Pivotaly attached to armatures 200 are perforating needles 5 as 201, so positioned adjacent the record sheet that when a perforating magnet is energized a perforation is made in the record sheet.

Perforating magnet 197 of section 196 records east bound train movements through blocks C, 10 D and E, and perforating magnet 198 records west bound train movements through blocks E, 15 D and C. Perforating magnet 199 records whether the train control rails represented by section 196 are energized with alternating current or not when there is a train movement in either direction in blocks C, D or E. As hereinbefore described, when blocks C, D or E are occupied by either an east bound or by a west bound train and switch 6 is in contact with either spring 20 contacts 18 or 19, relay 37 is sufficiently energized to attract its armature 96. Attached to armature 96 but insulated therefrom is a metallic contact plate as 202 and when armature 96 is in the energized position, this plate contacts with contacts 203 and 204 thus closing the circuit through perforating magnets 197 and 198 at this point. Also attached to switches 5, 6, 7 and 8 but insulated therefrom are metallic contact plates 205 and 206. When switch 6 is set up for an east bound train movement thus making contact with spring contact 18, metallic plate 205 makes contact with contacts 206 and 207, thus closing a circuit through perforating magnet 197 at this point. The circuit through perforating magnet 197 is as follows: From battery 190, wires 191 and 210, contact 211, contact plate 212, contact 213, bus 214, wire 215, perforating magnet 197, wire 216, contact 206, metallic plate 205, contact 207, wire 217, contact 203, metallic plate 202, contact 204, wires 218 and 194 to opposite side of battery 190.

When switch 6 is set up for a west bound movement thus making contact with spring contact 19, metallic plate 206 makes contact with contacts 208 and 209, thus closing the circuit through perforating magnet 198 as follows: From battery 190, wires 191 and 210, contact 211, metallic plate 212, contact 213, bus 214, wire 219, perforating magnet 198, wire 220, contact 208, metallic plate 206, contact 209, wires 221, and 217, contact 203, metallic plate 202, contact 204, wires 218, and 194, to other side of battery 190.

When switch 5 is in contact with spring contact 17 and there is a train in either blocks C, D or E a circuit is closed through perforating magnet 199 as follows: From battery 190, wires 191 and 210, contact 211, metallic plate 212, contact 213, bus 214, wire 222, perforating magnet 199, wire 223, contact 206, metallic plate 205, attached to switch 5, contact 207, wire 224, contact 203, metallic plate 202, contact 204, and wire 194 to the opposite side of battery 190.

It will be noted that the circuits through the perforating magnets are taken through a circuit breaking device as 212 so that these circuits are periodically made and broken. This circuit breaking device operates as follows: Metallic contact plate 212 is attached to armature 185 but insulated therefrom. Every time electromagnet 184 is energized which as hereinbefore stated is say every five seconds, the contacts 211 and 213 are closed through metallic plate 212. When electromagnet 184 is deenergized armature 183

is pulled to the right by spring 186 and the circuit through the perforating magnet is broken. By reason of this periodic breaking of the circuit a continuous perforation is made on the record sheet, as long as a section of single track consisting of blocks C, D and E is occupied by a train and switch 6 is in contact with either contacts 18 or 19 or switch 5 is in contact with spring contact 17. Thus when an east bound train leaves block B with signal No. 1, perforating magnet 197 will start to perforate in section 196 of the record sheet and perforating magnet 199 will start to perforate in the same section as soon as the train has entered block C and these two magnets will continue to perforate until the train has left block E, thus recording the exact time the train entered the single track section and also the time the train remained in the single track section. Should this train proceed through the section with No. 2 signal only, perforating magnet 197 will perforate and should it proceed through the section with signal No. 3, only, perforating magnet 199 will perforate. Thus not only a record is made of the train movements but also a record of the kind of signal displayed on the locomotive. Similarly a west bound train will record its movement through the section through perforating magnets 198 and 199.

30 A dispatcher having a number of single track sections under his control thus knows what progress the trains are making under his supervision and can direct the train movements with the greatest dispatch by properly positioning 35 the manually operable switches. The system lends itself to different methods of operation which the railway management may consider the most suitable for their particular purpose. One of the methods of operation would be as follows:

Assume that by reason of the accurate knowledge which the record sheet gives of the location 40 of trains on his division, the dispatcher decides to have an east bound train meet a west bound train at siding F. He also decides to favor the west bound train and therefore have the east bound train take the siding. In such case, he would then place switch 7 in contact with spring contact 17 and switch 8 in contact with spring contact 19, thus giving signal No. 1, the proceed 45 signal, to the west bound train, up to train control rail F15. He also would place switch 6 in contact with spring contact 18 but open switch 5 so as to disconnect it from spring contact 17. When the east bound train arrives at train control rail B12, signal No. 2, would be displayed on 50 the locomotive, thus indicating to the engineer to proceed to the next siding, siding F, pull in on the siding, and meet another train. Train control rail F15 being controlled by switch 6, and this switch being now in the east bound position, train control rail E15 would be deenergized and thus the west bound train would receive a danger signal sufficiently far back to 55 stop for the meet. If the east bound train, or any portion of it should be in block E, the west bound train would receive its danger or stop signal at train control rail G15, by reason of the track circuit control. As soon as the east bound 60 train has pulled in on the siding and cleared the main track the dispatcher is so advised by reason of the fact that perforating magnet 197 of section 196 has ceased to perforate. A further rule may also be provided, that the east 65 bound train crew should report to the dispatcher

by telephone, as soon as they are in on the siding and have cleared the main track. With the knowledge that the east bound train is clear of the main track the dispatcher may place switch 6 in contact with spring contact 19 thus giving 5 a proceed signal, signal No. 2, to the west bound train, at train control rail F14. It will be noted, however, that switch 6 was locked in the east bound position as long as the east bound train occupied either blocks C, D or E, and the dispatcher could not move switch 6 into the west bound position thus giving a clear signal to the west bound train at train control rail F14 until the east bound train was actually in the clear 10 on the siding. Similarly should the west bound train have reached block C or F, before the east bound train reached block E, a danger signal would be displayed to the east bound train at train control rails E12 and E13. In practice rails similar to train control rails as F13 would 15 also be placed adjacent to the siding on the right hand side of the center line thereof looking east, and energized or deenergized through the same circuit as train control rail F13. With this arrangement one of the track rails of the 20 siding would also be electrically connected to track rail 4. As soon as the west bound train has cleared the single track section east of block F, switch 8 is unlocked from its west bound position and the dispatcher may give a proceed signal 25 30 to the east bound train standing over the train control rail on the siding by placing switch 8 in the east bound position in contact with spring contact 18.

If the dispatcher desires to display signal No. 3 35 to a train indicating to the engineer to stop and report to the dispatcher, he first places switches 6 or 8 in contact with either spring contacts 18 or 19, depending upon which direction the train is running. He then places switches either 6 or 40 8 in the neutral or open position, so that they are disconnected from both spring contacts 18 and 19. He then places switches 5 or 7 in contact with spring contact 17 thus energizing the third rails for the section with alternating current only, which will result in the display of signal No. 3.

It is, of course, understood that in addition to the dispatcher's control of the signals additional safety is provided by means of the track circuit control. Trains approaching each other will 45 receive a danger signal, signal No. 4, when more than a block apart thus giving ample distance to bring the train to a stop, and a train following another will receive a danger signal, signal 50 No. 4, when within braking distance of the occupied block ahead.

The above is one method of operation under 55 which the system may be used but there are a number of other methods or modifications which will be evident to those skilled in train operation.

The modification shown in Fig. 3, is identical with Fig. 1, insofar as the circuits and recording means are concerned there is a difference, however, which consists in substituting fixed signals in place of the train control rails necessary for cab signals. The several blocks, track batteries, track relays and track relay armatures are identical with Fig. 1, as are also circuits from batteries 21 and 22 and alternating source in the dispatcher's office, through the several positions of switches 5, 6, 7 and 8. The circuits from polarized armature 26 of relay 25 to the train control rails are also identical except that for the train control rails two relays, as 225 and 226 at each 60 65 70 75

signal point are substituted. These two relays, with the circuits they control are shown in Fig. 3, opposite block F, and these signals control the entrance for a west bound train from block G into block F. This detail arrangement of circuits controlled by relays 225 and 226 is represented at other blocks, as 227 for east bound signals and 228 for west bound signals, the circuits controlling the fixed signals being identical for both directions. These relays may control both home and distant fixed signals in the manner well known to those skilled in the art.

It is thought sufficient to describe the circuits for the control of the west bound signals from block C to block F since the arrangement for other blocks for both directions is identical. In the detailed circuit diagram are shown four signals, designated as No. 1, No. 2, No. 3 and No. 4. These signals are controlled by direct current relay 225 and alternating current relay 226. When relays 225 and 226 are both energized signal No. 1 is displayed. When only relay 225 is energized signal No. 2 is displayed. When only relay 226 is energized signal No. 3 is displayed, and when both relays 225 and 226 are deenergized, signal No. 4 is displayed.

When switch 8 is in contact with spring contact 19, normal for a west bound movement, relay 225 is energized through the following circuit: From positive pole of battery 22, wires 48, 49 and 46, track rail 1, wire 229, resistance 230, wires 231 and 232, relay 225, wire 233, impedance 234, wires 235 and 236, front contact 14 of track relay F, armature 10, wire 237, front contact 75, of track relay e, wire 238, line wire 24, contact 28, polarized armature 26, of relay 25, wire 59, front contact 30, armature 29 of relay 25, wire 58, terminal 53, wire 52, terminal 51, wire 50, impedance 39, wire 38, relay 37, wire 36, shaft 35, switch 8, switch contact 19, wire 54, bus 55, impedance 56 and wire 57 to the negative pole of battery 22.

When switch 7 is in contact with spring contact 17, relay 226 is energized through the following circuit: From alternating current source 45 20, wire 60, condenser 61, bus 62, wire 63, spring contact 17, switch 7, shaft 35, wire 64, relay 65, wire 66, condenser 61, wire 68, terminal 51, wire 52, terminal 53, wire 58, armature 29, front contact 30, wire 59, armature 26, contact 28, line wire 24, wire 238, armature 11 of track relay e, front contact 75, wire 237, armature 10 of track relay f, front contact 14, wires 236 and 239, condenser 240, wire 241, relay 226, wires 242 and 231, resistance 230, wire 229, track rail 1, and wires 46, 49 and 106 to alternating current source 20.

Impedance 234 is placed in the circuit to prevent the flow of alternating current through the circuit, and condenser 240 is placed in the circuit to prevent the flow of direct current through the circuit. Resistance 230 is inserted in the circuit for the same purpose as resistance 145 is inserted in the cab circuit, that is, to reduce the flow of current through relays 37 and 65 in the dispatcher's office so as not to lock the switches 65 as hereinbefore described.

When relays 225 and 226 are both energized a circuit is closed through signal No. 1, as follows: From battery 243, wire 244, armature 245 of relay 226, front contact 246, wire 247, armature 248 of relay 225, front contact 249, wire 250, signal No. 1, wire 251, and wire 252 to opposite side of battery 243. When relay 225 only is energized a circuit is closed through signal No. 2, as follows: From battery 243, wire 244, armature 245, back contact 253, wire 254, armature

255 of relay 225, front contact 256, wire 257, signal No. 2, wires 258 and 252 to the other side of battery 243. When relay 226 only is energized a circuit is closed through signal No. 3, as follows: From battery 243, wire 244, armature 245, front contact 246, wire 247, armature 248, back contact 259, wire 260, signal No. 3, wires 261 and 252 to opposite side of battery 243. When both relays 225 and 226 are deenergized a circuit is closed through signal No. 4, as follows: From battery 243, wire 244, armature 245, back contact 253, wire 254, armature 255, back contact 262, wire 263, signal No. 4, wire 264, and wire 252 to opposite pole of battery 243. Relays 225 and 226 and battery 243 are properly housed near each signal location along the track.

While in the preferred form of my invention I have shown recording means to give the dispatcher knowledge of the location and progress of trains, I do not wish to be restricted to the recording means shown. Any means automatically indicating at the dispatcher's office the location and progress of trains may be considered an equivalent within the scope of my invention. For instance, the perforating magnets 197, 198 and 199 may be indication lamps which are lighted when their respective circuits are closed; thus visibly indicating the location and progress of trains. Or the perforating magnets 197, 198 and 199 may be any form of electrical translating devices which indicate when the circuits through them are closed; thus the position of armature 200 in itself may be a visible indication to the dispatcher of the location and progress of trains.

The purpose of the invention is to provide a simple and inexpensive system of signalling for a railway where a track is used for both directions of traffic. It is particularly adaptable to 40 single track uses but it is equally adapted for two or more track lines where it is desirable to use a certain track normally for one direction but at times to operate trains with dispatch and safety in the opposite direction.

Although I have particularly described one of the physical embodiments of my invention and illustrated the same, nevertheless I desire to have it understood that the particular form illustrated is merely illustrative and does not exhaust the possible physical embodiments of means underlying the principle of my invention.

What is claimed is:

1. In a railway dispatching system, a track-way having passing siding sections with main tracks and side tracks, said siding sections being separated by stretches of single track, each siding section having a signal station adjacent each end thereof for controlling the entrance of trains from the adjacent single track stretch into the siding section and each siding section having a signal station adjacent each end thereof for controlling the departure of trains from the passing siding section, each of the signal stations including different signals, the different signals of the first mentioned signal station being for indicating main track or side track operation, and each signal station having signal control means responsive to different kinds of currents supplied thereto for effecting display of said different signals, a dispatcher's office, a line circuit extending therefrom for each siding section, and associated with the signal stations of the siding section for supplying currents thereto, means at the dispatcher's office for impressing 75

- nating currents upon the line circuit and for reversing the polarity of the direct current, a relay in the line circuit at the siding section end thereof, said relay being responsive to the polarity of the direct current for applying the line circuit current to the ramp rails of the siding section for one or the other direction of traffic movement, a vehicle on the trackway having signal means selectively responsive to the presence 5 of direct current or both direct and alternating current for displaying different signal indications, and means at the dispatcher's office controlled over said line circuits for indicating the movement of the vehicle along the trackway.
- 15 7. In a railway dispatching system, a trackway having passing siding sections with main tracks and side tracks, said siding sections separated by stretches of single track, each siding section having a ramp rail adjacent each end thereof 20 for controlling the entrance of a vehicle from the adjacent single track stretch into the siding section and each siding section having a ramp rail adjacent each end thereof for controlling the departure of the vehicle from the passing 25 siding section, a dispatcher's office, a line circuit extending from the dispatcher's office for each siding section and associated with said ramp rails of the siding section, means at the dispatcher's office for impressing two different kinds 30 of currents upon the line circuits, a relay at each siding section associated with the line circuit and responsive to the polarity of one current in the line circuit for connecting to the line circuit the ramp rails for one or the other direction of 35 train movement, means at the dispatcher's office for changing the polarity of said one current in the line circuit, a vehicle on the trackway having signal means responsive to the presence of a current in the ramp rails for displaying a 40 proceed signal and responsive to the presence or absence of one kind of current in the ramp rail for displaying a main track and a side track indication, and means at the dispatcher's office controlled over said line circuits for indicating 45 the movement of the vehicle along the trackway.
- 45 8. In a railway dispatching system, a trackway having passing siding sections with main tracks and side tracks, said siding sections separated by stretches of single track, each siding section having a ramp rail adjacent each end thereof for controlling the entrance of a vehicle 50

from the adjacent single track stretch into the siding section and each siding section having a ramp rail adjacent each end thereof for controlling the departure of the vehicle from the passing siding section, a dispatcher's office, a line circuit extending from the dispatcher's office for each siding section and associated with said ramp rails of the siding section, means at the dispatcher's office for impressing two different kinds 5 of currents upon the line circuits, a relay at each siding section associated with the line circuit and responsive to the polarity of one current in the line circuit for connecting to the line circuit the ramp rails for one or the other direction of train movement, means at the dispatcher's office for changing the polarity of said one current in the line circuit, and a vehicle on the trackway having signal means responsive to the presence of a current in the ramp rails for displaying a proceed signal and responsive to 10 the presence or absence of one kind of current in the ramp rail for displaying a main track and a side track indication. 15 9. In a railway dispatching system, a trackway having passing siding sections with main tracks and side tracks, said siding sections being separated by stretches of single track, each siding section having a signal station adjacent each end thereof for controlling the entrance of trains from the adjacent single track stretch into the 20 siding section and each siding section having a signal station adjacent each end thereof for controlling the departure of trains from the passing siding section, each of the first mentioned signal stations including differentiated signals for indicating main track or side track operation and signal control means responsive to different kinds 25 of currents supplied thereto for effecting display of said differentiated signals, a dispatcher's office, a line circuit extending from said office for each 30 siding section and associated with the signal stations of the siding section, means at the dispatcher's office for impressing different kinds of currents upon the line circuits, a relay at each siding section associated with the line circuit 35 and responsive to the polarity of a current in the line circuit for establishing the signal stations for one or the other direction of train movement, and means at the dispatcher's office for changing the polarity of said current in the line circuit. 40 45 50 PAUL J. SIMMEN.
